PERFORATING MACHINE

Peter Juul, Chicago, Ill., assignor, by mesne assignments, to Bliss-Latham Corporation, Niagara Falls, N. Y., a corporation of Delaware

Application February 6, 1931. Serial No. 513,915

11 Claims. (Cl. 164—104)

The present invention is related generally to perforating machines, but more particularly to a novel and improved arrangement for supporting, locking and securing the punches thereof in operative or in inoperative positions.

One of the objects of the present invention is to provide a novel and improved construction of a quick, adjustable support for the punches of a perforating machine, in which a plurality of punches are supported therein so that the same may be adjusted to and locked in their normal operative positions or locked in their inoperative positions, so that different spacing between the perforations may be secured.

These and other objects are accomplished by providing a construction and an arrangement of the various parts in the manner hereinafter described and particularly pointed out in the appended claims.

Referring to the drawing:

Fig. 1 is a front elevational view of fragmentary portion of a perforating machine showing my invention embodied therein;

Fig. 2 is a cross-sectional view taken on the line 2—2 in Fig. 1;

Fig. 3 is a perspective view of the punch locking slug;

Fig. 4 is a side view of one of the punches; and

Fig. 5 is a cross sectional view taken on the line 5—5 in Fig. 1.

In illustrating one embodiment of my invention, I have shown the same in connection with a perforating machine of the construction described and illustrated in my U. S. Letters Patent No. 1,845,714, issued February 16, 1931, on a Perforating machine. This perforating machine, only a fragmentary portion of the same being shown in the drawing, comprises a reciprocating head generally indicated by the reference character 10 and a stationary bed generally indicated by the reference character 11. The opposite ends of the head 10 are suitably supported in guides (not shown) which may be of any well known construction. Extending longitudinally of the front face of the reciprocating head 10 is a recessed portion, as shown at 12, in which is secured by means of bolts 13, a punch supporting block 14. The punch supporting block 14 is provided with a plurality of vertically extending holes or bores 15, which are arranged in spaced apart relation. Mounted in these bores 15 are punches 16, 17, 18, 19, 20 and 21. The punches 16, 17 and 18 are identical in size but with relatively smaller punch heads, as shown at 22, than the punches 19, 20 and 21, as shown at 23. This

arrangement permits the punches 16 and 17 to be used in a pair, or the punches 16 and 18 to be used in a pair, so that different spacing of the same size perforations may be had. On the other hand, if a larger diameter of perforation 60 is required, the punches 19 and 20 may be used in a pair, or the punches 19 and 21 may be used in a pair to secure a different spacing of the perforations. Arranged contiguous with the bores 15 of the punch block 14 are recesses 24 which 65 are adapted to receive when the punches are in the normal operative position, pins 25 which are secured adjacent the upper ends of each of the punches 16, 17, 18, 19, 20 and 21. When the operator desires to withdraw certain punches 70 from their normal positions, that is, their normal operating positions, the punches are raised so that the pins 25 are withdrawn from the recesses 24 and seated in semi-circular recesses 26 located on the upper and outer edge of the punch 75 block 14. Each of the punches is provided on their front face with a rectangular recess as shown at 27. The recess 27 is located below the pin 25 and the bottom surface thereof and occupies a place substantially at right angles to the 80 axis of the pin 25. Each of the punches is provided above the recess 27 and at right angles with respect to the recess 27 with a second rectangular recess generally indicated by the reference character 28. Extending longitudinally 85 of the punch block 14 at a point slightly below the upper surface thereof, is a rectangular socket 29 which communicates with each of the bores 15 in the block 14. Mounted in the recess 29 is a removable punch locking slug or bar 30. This 90 locking slug or bar 30 is adapted to engage the recesses 28 of each of the punches when they are in their operative positions or the positions occupied by the punches 19 and 20, and is adapted to engage the recesses 27 when the punches are 95 in their inoperative position or the positions occupied by the punches 16, 17, 18 and 21. The slug or bar 30 is secured against displacement on the punch block 14 by means of cap screws 31, which are mounted in threaded engagement with 100 the block 14 so that the heads thereof engage the outer surface of the bar or slug 30 as clearly shown in Fig. 1 of the drawing. The bar 30 is provided with a notch as shown at 32 so the same may be removed by hand or with a tool after the 105 cap screws 31 are loosened.

Formed on the forward side of and overhanging the upper surface of the bed 11, is an L-shaped recess generally indicated by the reference character 33. Secured in the recess 33 by means of 110

bolts 34 is an L-shaped die 35. The upper surface or leg of the die 35 is provided with apertures—36, 37, 38, 39, 40 and 41, which are in registering alignment respectively with the 5 punches 16, 19, 17, 20, 18 and 21. These apertures 36, 37, 38, 39, 40 and 41 are adapted to co-operate with the punches when they are located in their operative position for perforating the material or paper as it is passed thereunder. Each 10 of these apertures, 36, 37, 38, 39, 40 and 41 communicates with enlarged apertures 42 extending vertically thru the beds 11 and which, in turn, communicate with an enlarged recess, indicated generally by the reference character 43 in the 15 lower portion of the bed 11 so as to allow for the escape of the waste material.

The operation of my improved perforating device is as follows: The punches 19 and 20 as shown in Fig. 1 of the drawing are in their operative 20 position, while the punches 16, 17, 18 and 21 are in their elevated or inoperative position. Let us assume that the operator desires to position the punches 16 and 18 in their operative positions and raise the punches 19 and 20 to their elevated 25 or inoperative positions. To accomplish this the cap screws 31 are loosened and the locking bar 30 removed. After this has been done, the punches 19 and 20 may be raised by gripping the upper end or head of the punch and raising the same 30 vertically, so as to disengage them from the sockets 24 in the block 14, then by rotating the punches a quarter of a turn, the pins 25 may be seated in the recesses 26. When punches 19 and 20 are thus positioned, recesses 27 will register with 35 the longitudinal recess 29, where they may be engaged by the locking bar 30 when the same is inserted. Then to lower the punches 16 and 18 to their operative positions, they are slightly raised so the pins 25 become disengaged from the semi- 40 circular recesses 25 and are turned a quarter of a turn in a cross-wise direction until these pins 25 register with the sockets 24 in the upper end of the block 14 after which they may be dropped in the socket so that the rectangular recesses 28 in 45 each of the punches 16 and 18 are in registering alignment with the longitudinal recesses 29 in the block 14. After this has been accomplished the bar 30 may be inserted and secured in place by the clamp screw 31, thereby positioning the 50 punches 16 and 18 in their lowered or operative positions, while the remaining punches are raised and locked in their inoperative positions so that upon a reciprocation of the head 10 in cooperation with the die 35, the paper passing therethrough will be perforated by the two punches 16 and 18. In a similar manner any set of punches 55 may be adjusted and locked in their operative position on the head while the remaining punches may be raised and locked in their inoperative 60 positions on the head.

While in the above specification I have described one embodiment which my invention may assume in practice, it will, of course, be understood the 65 same is capable of modification and that modification may be employed without departing from the spirit and scope of the invention as expressed in the following claims.

What I claim as my invention and desire to 70 secure by Letters Patent is:

1. The combination with a perforating machine, of a reciprocating head therefor, a punch block secured to said head, a plurality of punches carried by said head and single means for locking certain of said punches in operative position and

certain other of said punches in inoperative positions on said block.

2. The combination with a perforating machine, of a reciprocating head therefor, a punch block secured to said head, a plurality of punches carried by said block, and a slug for locking certain of said punches in operative position and certain other of said punches in inoperative position on said block. 80

3. The combination with a perforating machine, of a reciprocating head therefor, a plurality of punches carried by said head, and removable single means for locking certain of said punches in operative position on said head and certain other of said punches in inoperative position on 90 said head.

4. The combination with a perforating machine, of a reciprocating head therefor, of a plurality of punches carried by said head, and a removable slug carried by said head and engageable with said 95 punches for removably locking certain of said punches in operative position on said head and certain other of said punches in inoperative position on said head.

5. The combination with a perforating machine, of a reciprocating head therefor, a plurality of punches carried by said head, there being a plurality of recesses formed in said punches, a removable slug carried by said head and adapted to engage certain recesses in said punches for locking certain of said punches in operative position 105 on said head and certain other of said punches in inoperative position on said head.

6. The combination with a perforating machine of a reciprocating head therefor, a punch 110 block secured to said head, a plurality of punches carried by said block, there being a longitudinal slot in said block, said punches having a plurality of recesses formed in the periphery thereof and a removable slug mounted in said 115 slot and adapted to engage the recesses in said punches for locking certain of said punches in operative position on said block and certain other of said punches in inoperative position on said block. 120

7. The combination with a perforating machine, of a reciprocating head therefor, a punch block secured to said head, having a plurality of spaced apart and vertically extending bores therein, there being a plurality of sockets formed 125 in the upper end of said block communicating with said bores, a plurality of punches removably mounted in said bores and having laterally projecting pins adapted to removably engage said sockets formed in the upper end of said block, 130 and means removably secured in said block adapted to engage said punches for locking certain of said punches in operative position on said block and certain other of said punches in inoperative position on said block. 135

8. The combination with a perforating machine, of a reciprocating head therefor, punch block secured to said head, having a plurality of spaced apart and vertically extending bores therein, there being sockets formed in said block adjacent the upper ends of each of said bores, a plurality of punches mounted in said bores, laterally extending pins secured to said punches and adapted to be seated in said sockets, there being a plurality of spaced apart recesses formed 145 in said punches, a longitudinal slot formed on the face of said block, and a removable bar mounted in said slot and adapted to engage the recesses formed in said punches for locking certain of said punches in operative position on said 150 block.

block and certain other of said punches in inoperative position on said block.

9. A punch supporting structure for perforating machines, comprising a frame, there being a plurality of bores in said frame, a plurality of punches mounted in said bores, means for locking certain of said punches in operative position on said frame, means formed on said punches and adapted to engage said frame for supporting certain of said punches in operative position on said frame and for supporting certain other of said punches in inoperative position on said frame, and means for locking said punches to said frame.

10. A punch supporting structure for perforating machines comprising a frame having a plurality of vertically extending and laterally spaced apart bores formed therein, a plurality of punches in said bores, means formed on said punches for sustaining said punches in operative position on said frame, and means whereby

said punches may be raised and slightly revolved into a position for sustaining said punches in inoperative position on said frame, said punches having a plurality of slots in the periphery thereof, and a removable member secured to said frame for engaging certain of said recesses formed in said punches for securing certain of said punches in operative position on said frame and certain other of said punches in inoperative position on said frame.

11. A removable punch supporting construction for perforating machines comprising a frame, a punch mounted on said frame, means for supporting the punch in either of two positions on said frame, said positions being reached by the punch by raising and revolving the punch, and means for locking the punch in either of the two positions.
